UNITED STATES PATENT OFFICE.

ASHER LAMBERT, OF NEWARK, NEW JERSEY.

ELECTRIC DRIVE FOR HOISTING AND BOOM-LIFTING DRUMS.

1,181,322.

Specification of Letters Patent.

Patented May 2, 1916.

Application filed April 29, 1915. Serial No. 24,683.

To all whom it may concern:

Be it known that I, ASHER LAMBERT, a citizen of the United States, residing at 1 Johnson avenue, Newark, county of Essex, 5 and State of New Jersey, have invented certain new and useful Improvements in Electric Drive for Hoisting and Boom-Lifting Drums, fully described and represented in the following specification and the accompanying drawings, forming a part of the same.

This invention relates to a three-drum hoisting-machine for excavating with a clam-shell bucket which can be opened and 15 closed by two ropes connected to separate drums. One of such drums requires much more power than the other, as it is used to close the bucket and hoist the same with its load, while the other drum is employed to 20 open and dump the bucket. The third drum in the hoister requires more power than any of the others when it is used to raise and lower the boom which carries the bucket-ropes and the loaded bucket. The drums in 25 such a machine may be otherwise used but, for convenience, the three will be referred to herein as the boom-drum, the hoisting-drum and the dumping-drum.

It is the object of the present invention to 30 obviate some of the frictional losses in such a hoister by locating an electric motor on a bridge connecting the side-frames with its armature-shaft between two of the drums, and meshing its pinion directly with spur-gears upon those drums, thus operating to 35 rotate them in the same direction; direct gearing also being furnished to connect the third drum with one of the two, and operating to rotate such third drum in a direction opposite to the others. This arrangement of the motor and its shaft avoids the 40 use of any intermediate gear whatever between the pinion and the gear for either of the drums which uses much power.

To relieve the motor-bearings from the 45 strain exerted by the pinion, the armature-spindle is provided (outside of the pinion) with a bearing upon the frame of the bed, thus supporting the pinion firmly and 50 avoiding wear of the armature-bearings.

It is very desirable that the motor-spindle should not be reversed by the pull upon the ropes when the current is cut off from the motor to stop the drum; and to prevent such 55 a reversal of the armature-spindle, it is

provided with a brake-wheel having a strap operated by a tension-lever and so constructed as to permit the free rotation of the armature-spindle during the hoisting operation, but operating positively and automatically to arrest the same when the current is cut off from the motor.

The invention will be understood by reference to the annexed drawing, in which—

Figure 1 is a side elevation of the hoister 65 with the brake-wheel and brake-blocks omitted in the brake of the armature-spindle; Fig. 2 is a plan of the hoister; and Fig. 3 shows an alternative construction of the gearing for the dumping-drum.

a, a' designate the side-frames, and *b, b'* the cross-bars of a bed, which carries upon each of the side-frames bearings *c, d* and *e* for the drum-shafts *f, g* and *h* of the boom-drum *f'*, the hoisting-drum *g'* and the 70 dumping-drum *h'*. The shafts *f* and *g* are provided with spur-gears *c'* and *d'*, and the shafts are spaced apart so that there is room between the adjacent edges of the spur-gears for the pinion *i* upon the armature-spindle *j* 75 of the motor *k*. The spur-gears *c'* and *d'* are made very large relatively to the pinion so as to sufficiently reduce the speed of the drums in such a direct connection to the armature-spindle. The spur gears *c'* and *d'* 80 are secured to their shafts close to the bearings *c* and *d* upon the side-frame *a'*, and a bearing *l* is provided upon the same side-frame for the armature-spindle *j*, upon the 85 outer side of the pinion *i*.

The motor is mounted upon a bridge *m* extended between the side-frames *a, a'*, and a brake-wheel *n* is attached to the armature-spindle at the end opposite that which carries the pinion. The strap *n'* for the brake-wheel *n* is shown in Fig. 2, the brake-wheel itself being omitted to show the motor more clearly; but the crank *n* for operating the brake-strap is shown, with an arm projected from it and connected to a tension-spring *s*. 100 The crank has two crank-pins *s* and *s'* disposed at unequal distances from the fulcrum *n* of the crank, which crank-pins are connected to the opposite ends of the brake-strap *n'*.

The normal rotation of the armature-spindle which winds up the ropes *F* and *G*, as indicated by the arrows *t* upon the ropes in Fig. 1, tends to loosen the brake-strap; which remains loose, as well as the spindle, 110

when turning in its working direction, which is effected without any strain or friction of the strap; as the spring s^2 is adjusted to produce little, if any, resistance to such movement of the brake-strap. The rocking of the crank upon its fulcrum under the tension of the spring draws up one end of the brake-strap a little more than it lets out the other end, thus producing an automatic tightening of the strap if the brake-wheel n of Fig. 1 attempts to turn in a direction reverse to its normal movement. The automatic braking of the armature-spindle serves to prevent the rope-drums from turning backward so long as they are connected with their friction-drivers p .

Ropes F and G are shown extended in a slanting direction from the upper sides of the drums f' and g' , and a rope H extended from the under side of the drum h' , and such ropes may be extended upward to an elevated point upon the post of a derrick, where they may be guided over pulleys to raise and lower the boom or the bucket. The rope F is thus arranged to clear the top of the motor h , the spindle of which is shown set upon the same level as the drum-shaft f , but where it is desired to carry the ropes to the foot of the derrick-post, the bearing c of the drum f' may be made higher, so that the rope F may pass horizontally over the top of the motor.

The shaft h of the dumping-drum h' is shown provided with a spur-gear e' , and a similar spur-gear e^2 is attached to the shaft g of the drum g' , the two gears meshing directly so that these two drums turn in opposite directions, but at exactly the same speed.

In a three-drum hoister where the dumping-drum h' operates in conjunction with the hoisting-drum g' to first close and raise the bucket with a load and then to open and dump the bucket, it is absolutely necessary that the surface-speed of the two drums should be the same, so that during the hoisting operation the dumping-rope may be wound up simultaneously with the hoisting-rope so as to hold the bucket closed until it requires dumping.

A pair of equal spur-gears e' and e^2 is shown in Fig. 2 for connecting the shafts of the hoisting and dumping-drums, which are shown of the same diameter and must therefore be rotated at exactly the same speed; and such identity of speed could not be secured by connection to the spur-gear d' without providing the shaft h with an equally large spur-gear; which would crowd the drums g' and h' a great distance apart and unnecessarily lengthen the bed of the entire hoister. For that reason, a pair of smaller spur-gears e' and e^2 is employed; but where the speed of the drum h' permits, its spur-gear e' may be meshed directly with

the gear d' , as shown in Fig. 3. Such an arrangement increases the speed of the drum h' , but the same may be made smaller, as shown in Fig. 3, to equalize its rope-delivery more nearly with that of the drum g' .

As the drums g' and h' revolve in opposite directions, the ropes G and H may be made to hoist or lower simultaneously by winding them upon their drums in opposite directions, as shown in Fig. 1; the rope G running from the top of the drum g' , and the rope H running from the bottom of the drum h' .

It will be understood that the connection between the shafts g and h is equally direct whether the spur-gear e^2 is employed as in Fig. 2, or omitted as in Fig. 3; because the friction in either case is merely that of one spur-gear running into another.

The drums f' and g' are provided with brake-wheels f^2 and g^2 , and the drum h' with a brake-wheel h^2 , the straps for such brakes being shown in Fig. 1. The levers of these brake-straps are controlled solely by the operator.

Each of the drums is mounted to turn loosely upon its shaft, and is provided with a hollow cone o adjacent to its spur driving-gear, which latter is provided with a wooden friction-cone p to fit the hollow cone. A thrust-screw q is provided for each drum. It will be observed in Fig. 2 that the pinion i has an equally direct connection with the gears c' and d' of the drums f' and g' , which wholly avoids the use of any intermediate gears in the transmission of power to the two drums which require the greatest amount of power in the operation of the hoister.

The shaft of the drum h' is driven by a direct connection to the shaft g of the drum g' , and is thus driven with only a single intermediate, represented by the spur-gear d' or e^2 .

The present improvements are simple in their nature and economical in construction, and add materially to the efficiency of the three-drum hoister.

Having thus set forth the nature of the invention what is claimed herein is:

In a three-drum hoisting machine, the combination, as herein described, of a bed having side-frames, and bearings upon the same for the shafts of three drums, drums mounted upon shafts in the bearings, two adjacent drums having spur-gears with their edges a little distance apart, a bridge connecting the side-frames between the said two drums, an electric motor mounted upon the bridge with its armature-shaft extended over one of the said frames, and provided with a bearing thereon, and having a pinion between the said bearing and the motor, meshing directly with the gears of the said two drums and operating to rotate the two

gears simultaneously in the same direction, direct gearing connecting the shaft of one of the said drums to the shaft of the third drum and operating to rotate the two in opposite directions, a brake-wheel upon the armature-shaft, and a brake with brake-shaft and a tension-lever adapted to yield

10 during the normal rotation of the motor-shaft, and operating to positively prevent the reversal of such motor-shaft.

In testimony whereof I have hereunto set my hand.

ASHER LAMBERT.
